CLAIM

The ornamental design for a blister package, as shown and described.

DESCRIPTION

FIG. 1 is a perspective view showing our new design for a blister package;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a perspective view showing a second embodiment of our new design wherein the modification resides in the addition of a backing sheet.
